Primary Examiner — W. A. Teddy Falloway*Assistant Examiner* — Sarah J Ault(74) *Attorney, Agent, or Firm* — Law Offices of Alozie N. Etufugh, PLLC(57) **CLAIM**

The ornamental design for a pendant, as shown and described.

DESCRIPTION

FIG. 1 is a front perspective view of a pendant showing my new design;

FIG. 2 is a right side view thereof;

FIG. 3 is a left side view thereof;

FIG. 4 is a front view thereof;

FIG. 5 is a rear view thereof;

FIG. 6 is a top view thereof;

FIG. 7 is a bottom view thereof; and,

FIG. 8 is a front view of the pendant of FIGS. 1-7 showing a stone region in a changed state of appearance relative to FIGS. 1-7. The stippling shown on the stone region in FIG. 8 represents a contrast of appearance with respect to the remaining stones and the change of state is affected.

It will be understood that the broken lines presented in the drawing are for illustration purposes only, and do not form a part of the claimed design.
